COMBINED WATER CLOSET BOWL AND SEAT

Minoru Sakamoto, 3911 Nioi Place,
Honolulu, Hawaii 96816

Filed Feb. 21, 1973, Ser. No. 334,207

Term of patent 14 years

Int. Cl. D23—02

U.S. Cl. D23—67

Fig. 1

Fig. 3

Fig. 2

Fig. 4

FIG. 1 is a top plan view of a combined water closet bowl and seat showing my new design;

FIG. 2 is a front elevational view thereof;

FIG. 3 is a rear elevational view thereof; and

FIG. 4 is a side elevational view thereof.

The broken line representation of a water tank in FIGS. 1, 2 and 4 is for purposes of illustration only.

I claim:

The ornamental design for a combined water closet bowl and seat, as shown and described.
